UNITED STATES PATENT OFFICE.

GEORGE LANE, OF Poughkeepsie, New York, Assignor to LANE BROTHERS COMPANY, OF Poughkeepsie, New York, a Corporation of New York.

LEAVING JACK.

1,181,805.

Specification of Letters Patent.

Patented May 2, 1913.

Application filed January 15, 1912. Serial No. 22,897.

To all whom it may concern:

Be it known that I, George Lane, a citizen of the United States, residing at Poughkeepsie, New York, have invented certain new and useful Improvements in Lifting-Jacks, of which the following is a specification.

My present invention relates to improvements in lifting jacks of the step up and 10 step down type and is designed more especially as an improvement upon the form of jack shown in Letters Patent of the United States No. 1,122,235, granted to me on the 22nd day of December, 1911. Such jacks 15 are very largely used for elevating the axles of automobiles, and as ordinarily constructed it is necessary for the operator to reach or crawl under the machine to place the jack in position and operate it, resulting in the 20 soiling of clothing and the work being performed in an inconvenient and uncomfortable position, and in the case of heavy machines rendering it difficult to apply the necessary power to the hand lever.

25 My said invention aims to provide a jack with an operating lever of such length and so connected with the jack that it may serve as the means for placing the jack in operative relation to the axle from a point clear 30 of the body of the automobile.

A further object is to provide such a lever arranged or provided with means operable from the handle portion of the lever for controlling the mechanism which operates the lifting bar to determine whether 35 it shall lift or lower the load.

With these and other objects in view, the 40 invention includes the novel features of construction and arrangement and combination of parts hereinafter described and particularly defined by the appended claims, my preferred embodiments of the invention being illustrated in the accompanying drawings, in which—

45 Figure 1 is a sectional elevation of a sufficient portion of a jack to illustrate my invention. Fig. 2 is a sectional detail of the socket member showing the hand lever in one position. Fig. 3 is a similar view showing said hand lever in another position. Fig. 4 is a view similar to Fig. 1 looking at the opposite side. Fig. 5 is a sectional detail. Fig. 6 is a side elevation of a complete jack showing the hand lever in operating position. Fig. 7 is a perspective view

of the hand lever detached. Fig. 8 is a view similar to Fig. 1, showing a modification. Fig. 9 is a sectional detail. Figs. 10 and 11 are respectively a side elevation and a plan of the hand lever used in connection with this form. Figs. 12, 13 and 14 are detail views of a still further modification.

Referring by reference characters to these drawings, the numeral 1 designates the base, 2 the standard, 3 the lifting bar guided therein, and 4 and 5 the retaining and lifting pawls, the former pivoted to the standard and the latter to the lifting lever 6 having a socket 6^a to receive the operating or handle bar 7. Said pawls, as in my aforesaid patent, are connected by springs 14 and 13 to the bell crank levers which are connected by spring C, and as they operate in the manner stated in detail in the specification of said patent, further description thereof herein is deemed unnecessary.

The hand lever, indicated at 7, is made long enough to extend from a point beneath the axle of the automobile to a position outside the body of the machine. To enable the operator to use the handle as a means for positioning the jack beneath the car axle, I provide means for retaining its forward end in the socket 6^a of the lever 6, and such means may take the form of a dog engaging a notch in the handle bar and pressed normally inward into engaging position by a spring having a deflected end or finger piece to enable the dog to be withdrawn for removal of the handle.

It will be understood that when the inner ends or shoulders 11^b and 12^b of the bell crank levers are unobstructed, the operation of the lever 6 effects an upward step by step movement of the lifting bar, while, when the movement of said ends is alternately obstructed, a step by step lowering of the bar takes place. In the present instance, I employ as an obstructing device a cross bar 21 carried by an arm 21^a having a horizontal pivot portion 21^b journaled in the lever 6. These parts may conveniently be made in the form of an open loop, as shown in Fig. 5. A spring 22 tends to keep cross bar 21 and arm 21^a normally in the position shown in full lines, Figs. 1 and 4, in which position said cross bar will alternately contact with the portions 11^b and 12^b of said bell crank levers and rock them to place tension alternately on the springs 13 and 14 in

and thus control the dogs to effect the lowering of the lifting bar.

To cause the dogs to operate to effect the step by step raising of the lifting bar, it is only necessary to move the contact piece or arm 21 into such position that, during the rocking movements of the lever 6, it will be ineffective with relation to the arms or portions 11^b and 12^b of the bell cranks 11 and 12. A convenient means of effecting this removal of the contact member is to connect the handle to the lever 6 in such a manner that while said hand lever is connected to the lever 6 with sufficient permanence or rigidity to enable the jack to be placed into position beneath the car axle, yet the hand lever is capable of a limited movement in the socket 6^a so as to shift the contact piece into such a position that it will not contact with said portions or shoulders 11^b and 12^b. In the embodiment shown in Figs. 1 to 7, I have arranged the hand lever in such a position that it is capable of a lengthwise movement in the socket and provide it with a projection 18^a designed to contact with a portion of the contact piece or bar 21 at one side of the bell crank levers, so that when the hand lever is pushed into its extreme inward position, said projection 18^a will force contact piece 21 forward into the position shown in dotted lines in Fig. 1, where it will be inoperative with respect to the bell crank levers. A limited outward movement imparted by a pull upon the hand lever will draw said projection away from the contact piece 21, allowing the spring 22 to throw the latter back into operative position with the said portions 11^b and 12^b of the bell crank levers. To enable this movement of the hand lever to take place by mere push or pull thereon without affecting the connection which enables the hand lever to serve as the means for positioning the jack, I provide the inner end of the hand lever with two notches 18^b and 18^c respectively and I form the dog 19 with one abrupt face 19^a and one inclined face 19^b. The recesses 18^b and 18^c are so arranged that when recess 18^b is engaged by the dog, the projection 18^a of the hand lever is in such position as to render the contact piece 21 operative to effect the lowering of the jack, while when the recess 18^c is engaged by the dog the projection 18^a has swung the contact piece into ineffective position so that the pawls or dogs 4 and 5 will be effective to raise the lifting bar. The recess 18^b is provided with an abrupt face to correspond to the abrupt face 19^a of the dog, so that the hand lever cannot be pulled completely out of the socket without withdrawing the dog by the thumb piece on the spring. The opposite wall *b* of the recess is inclined to correspond to the face 19^b of the dog, the inclination being such that any

push upon the hand lever will cause the dog to be pressed outward by the cam action against the tension of the spring until it alines with recess 18^c and is projected thereinto, in this position said dog retaining the hand lever in lowering position. Said recess 18^c has one face *b* corresponding in inclination to the face 19^b of the dog while the other face is inclined to such an extent that with the dog engaging the recess 18^c, an outward pull upon the handle will cause said inclined face to act as a cam to force the dog outward until it has alined with and sprung into the recess 18^b. In either position the dog engages the corresponding recess with sufficient holding force to enable the hand lever to be used as the means for manipulating the jack.

In order for the operator to place the jack beneath the axle of an automobile and operate it without getting under any part of the body of the machine, it will be obvious that a hand lever of considerable length is necessary. Such a hand lever would be too long to be conveniently carried in any of the tool receptacles with which automobiles are provided and to this end I provide a folding handle comprising a plurality of parts with means for rigidly connecting said parts when the handle is unfolded or extended. Such a hand lever is shown in detail in Figs. 6 and 7, comprising two members or bars 7^a and 7^b pivotally connected by a pivot pin or bolt 7^c, one of the members having a flange or lug 7^d adapted to bear against the under edge or face of the adjoining bar to render the two parts rigid as regards downward movement, which is the only time any strain is applied to the hand lever. At the same time the parts can be folded upwardly and over upon each other for placement in the tool receptacle.

Instead of shifting the reversing mechanism by a longitudinal movement of the entire hand lever, as hereinbefore described, I may desire to provide a separate part or rod carried by the hand lever and adapted upon insertion of the end of the hand lever in the socket to be brought into operative position for the shifting of the dog or abutment which coacts with the bell crank levers, so that the reversal of the jack may be effected by the reciprocation of this rod instead of the entire hand lever. Such an embodiment of my invention is shown in Figs. 8 to 11. In this construction the inner end of the hand lever would be locked rigidly within the socket by having the dog 18^x engaged with a single recess *x* in the handle bar or lever and the controlling bar or member 21 would be shifted against the tension of its spring by a longitudinally movable rod 24 suitably guided by the handle bar as by means of eyes 25. In this form I

have shown the contact member 21 as adapted to be normally pressed toward the hand lever by a spring and in this position to be ineffective by reason of recessed portions 5 11^x and 11^y of the bell crank levers 11 and 12, said contact member 21 being adapted to be pressed forward against the tension of the spring by the rod 24, which rod may be provided with suitable means for engaging 10 the hand lever or bar to retain it in its forward position, as for instance notch 24^x to engage rearmost eye 25.

Instead of having a movement of the bar or contact piece 21 effected by a longitudinal 15 movement of the handle bar, as in the first form above described, or by the longitudinal movement of a separate rod carried by the handle bar, as in the second form, I may accomplish this result by a rotary movement 20 of the handle bar. In this event the handle bar would have a cylindrical end, indicated at 7^x, to fit into a correspondingly shaped socket, being retained therein by a spring dog y, fitting in a circumferential groove y', 25 extending part way around said cylindrical portion of the handle bar. The inner end of the handle bar would be provided with a cam portion, which in one position of the handle bar would allow the contact piece 21 to be pressed outwardly by the spring, while in another position the cam portion of the handle bar would force said contact piece in the opposite direction. In the embodiment shown in Figs. 12 to 14, the cam portion 30 is formed by providing the inner end of the handle bar 7^x with a V shaped depression 7'. When this cylindrical portion is in the position shown in Fig. 12, the contact member 21 would rest at the bottom of 35 the V shaped depression, while when given a quarter turn to the position indicated in Fig. 13, the contact piece 21 will be forced backward by the edge of the V shaped slot acting as a cam.

45 What I claim is:—

1. A lifting jack comprising a standard, a lifting bar movably guided thereby, mechanism for moving the lifting bar upward by a step by step movement and downward 50 by a similar movement, said mechanism including an operating member, a handle bar connected to said operating member to have a limited bodily movement in relation thereto, and means controlled by said bodily movement of the handle bar for determining whether said mechanism shall move the lifting bar up or down.

2. A lifting jack comprising a standard, a lifting bar movably guided thereby, mechanism for moving the lifting bar upward and downward by a step by step movement respectively, said mechanism including an operating member having a socket, a handle bar having an end held in said socket to 55 have limited movement therein, and means

controlled by said limited movement to determine whether said mechanism shall move the lifting bar up or down.

3. A lifting jack comprising a standard, a lifting bar movably guided thereby, mechanism for moving the bar upward and downward, said mechanism including a rocking member having a socket, a hand lever having an end detachably held in said socket to have relative movement therein while so held, and means controlled by said relative movement of the hand lever to determine whether said mechanism shall raise or lower the lifting bar.

4. A lifting jack comprising a standard, a lifting bar movably guided thereby, mechanism for moving the bar upward and downward, said mechanism including a rocking member having a socket, a hand lever having an end detachably held in said socket and being, while so held, shiftable into either of two positions, said hand lever having a pair of notches and a dog carried by the rocking member to coact with said notches in the hand lever to retain it in either position, and means controlled by the position of the handle bar in the socket for determining the direction of movement of the lifting bar.

5. A lifting jack comprising a standard, a lifting bar movably guided thereby, mechanism for moving the bar upward and downward, said mechanism including a rocking member having a socket, a hand lever having an end slidably fitting said socket and having a pair of notches, one face of one of said notches being an abrupt face, and the other inclined, a spring pressed dog carried by said rocking member having an abrupt face and an inclined face for cooperating with said notches, means for withdrawing the dog from engagement with said notches, and means controlled by the position of the hand lever in said socket as defined by the engagement of the dog with the notches for determining the direction of movement of the lifting bar.

6. A lifting jack comprising a standard, a lifting member guided thereby, an actuating lever, a lifting pawl and a holding pawl 115 cooperating with said lifting bar, a spring for normally pressing said pawls into operative relation to the lifting bar, a separate spring connected to each pawl, means on the actuating lever for alternatively applying tension to said separate springs and a member movable longitudinally of the actuating lever for rendering said tension applying means ineffective when desired.

7. A lifting jack comprising a standard, a lifting bar guided thereby, a holding pawl pivotally connected to the standard to engage the ratchet bar, an actuating lever, an operating pawl pivoted to the lever to engage the lifting bar, spring means for press- 120

- ing said pawls normally toward the ratchet bar, contact means on the actuating lever for alternatively applying yielding tension to said pawls, said contact means being movable longitudinally of the operating lever and a separate member movably carried by said actuating lever for shifting said contact member into and out of operative position.
10. 8. A jack comprising a standard or guide, a lifting bar, an actuating lever, a lifting pawl and a holding pawl coöperating with said lifting bar, a pair of spring pressed bell crank levers pivotally supported from the standard and adapted to press said pawls toward the lifting bar, springs connecting said bell crank levers with the pawls, a contact piece movably carried by the actuating lever and having a contact portion adapted to contact with said bell crank levers in one position of the contact device and a handle bar for said actuating lever carrying a part which is movable with respect to the actuating lever for determining the position of said contact device.
9. A jack comprising a standard or guide, a lifting bar, an actuating lever having a socket, a lifting pawl and a holding pawl coöperating with said lifting bar, a pair of spring pressed bell crank levers pivotally supported from the standard and adapted to press said pawls toward the lifting bar, springs connecting the said bell crank levers to the pawls, a contact device movably carried by the actuating lever and having a contact portion adapted to contact with said bell crank levers in one position of the contact device and movable to another position to be ineffective with respect to said bell crank levers, and a hand lever having a portion normally held in said socket and movable while so held to shift said contact device against the tension of its spring, substantially as described.
45. 10. A lifting jack comprising a standard, a lifting member guided thereby, an actuating lever, a lifting pawl and a holding pawl coöperating with said lifting bar, a spring for normally pressing said pawls into operative relation to the lifting bar, a separate spring connected to each pawl, means on the actuating lever for alternatively applying tension to said separate springs, a spring tending to keep said means pressed normally in one direction and a handle bar movably connected with the actuating lever and having a part adapted by movement of the handle bar while so connected to shift said means against the tension of its spring.
11. A lifting jack comprising a standard, a lifting bar guided thereby, an actuating lever having a socket, a lifting pawl and a holding pawl coöperating with said lifting bar, a spring for normally pressing said pawls into operating relation to the lifting bar, a pair of bell crank levers pivoted to said actuating lever, springs connecting said bell crank levers with said pawls, a contact piece carried by the actuating lever and longitudinally movable of the actuating lever and adapted when in one position to contact alternately with said bell crank levers under the rocking movement of the actuating lever and in another position to avoid such contact, said contact piece having a part extending into the socket of the actuating lever, a spring for forcing said contact piece in one direction and a handle bar adapted to be inserted in said socket and having a part adapted to actuate said contact device against the tension of its spring.
- In testimony whereof, I affix my signature in presence of two witnesses.
